UNITED STATES PATENT OFFICE.

GEORGE KOWALSKI, OF McDOWELL, WEST VIRGINIA.

SAFETY DOOR FOR SAFES.

Application filed March 6, 1926. Serial No. 92,824.

This invention relates generally to safes, bank vaults and the like, the invention having more particular reference to a novel type of supplementary safe door.

- 5 The invention has for an object the provision of an improved supplementary safe door which may be automatically operated so as to render the safe or vaults to which same is attached burglar proof.
- 10 Another object of the invention is to provide a safe door of novel construction and arrangement of parts.

For further comprehension of the invention, and of the objects and advantages 15 thereof, reference will be had to the following description and accompanying drawing, and to the appended claims in which the various novel features of the invention are more particularly set forth.

- 20 Fig. 1 of the drawing, shows a perspective view of a safe with my improved safe door attached thereto.

Fig. 2 shows an enlarged view partly in section of certain parts of the operating 25 mechanism as used in connection with my improved device.

Fig. 3 shows an enlarged perspective view 30 of other parts of the operating mechanism as used in connection with my improved device.

The safe, vault, or safety deposit box, designated by the reference number 10, has a door 11, and is imbedded in the wall 12, of a building, having a floor 13. The above 35 mentioned articles and elements are of common design and construction, such as ordinarily used.

As here embodied my improved device 40 comprises a supplementary safe door 14, of suitable dimensions to enclose or cover the front of the safe 10. The supplementary safe door 14 is slidably located in the vertical guides 15 and 16, one of the said vertical guides extends to the bottom of the safe 10, 45 as at 17, and has a rack 18 formed therein or attached thereto, suitably located to mesh with the gear 19, which is rotatively mounted on a shaft 20, rigidly attached to the supplementary safe door 14, the operating 50 handle, or crank 21, is rigidly attached to the gear 19, the above mentioned construction being such as will permit the supplementary safe door 14 to be raised or extended above the safe door 11, as clearly 55 shown in Fig. 1, of the accompanying drawing. It will be understood that the here-

before mentioned guide 16 does not extend past the safe door 11, but that the supplementary safe door 14 is of suitable height to engage the lower portion of the guide 16, 60 when the supplementary safe door is in a lowered or closed position.

The catch 22 is pivotally attached to the back of the supplementary door 14, as at 23, and has an offset extremity 22' provided 65 with a notch 24.

The catch lever 25, is pivotably attached to the wall 12, as at 26, preferably at or near its center, and has an upper offset portion 27 provided with a pointed extremity 70 28, to engage the notch 24 of the catch 22. The horizontal bar 29 is slidably located in the support 30, which is rigidly attached to the wall 12, as at 31, and is suitably located and has a yoke 32 at one extremity 75 which is pivotally attached to the elongated aperture 33 located in the lower extremity of the catch lever 25, by means of the pin 34, rigidly attached to the yoke 32 and extended through the elongated aperture 33. 80 The horizontal bar 29 has formed at its upper edge a plurality of grooves or notches 35. The locking pin 36, is a slidable fit in the aperture 41 of the bracket 37, which is attached to the wall 12, as at 38. The locking pin 36, has a pointed lower extremity 85 39, which may be held in engagement with any desired one of the grooves 35 by the coil spring 40, which is located in the aperture 41, and superimposed between the 90 upper extremity of the locking pin 36 and the bottom of the cap 42, which is threadedly attached to the bracket 37, as at 43, it being understood that the force of the coil spring 40 may be increased or decreased by screwing 95 the cap 42 downwards or upwards.

The extremity 44 of the horizontal bar 29 is a slidable fit in the adjustable member 45, which is provided with an aperture 46, at or near its outer extremity to accommodate a cord 47, chain, or flexible member. The extremity 44 of the horizontal bar 29 is provided with a plurality of apertures 48, of equal number and spaced the same distance apart as the heretofore mentioned grooves 35 in the bar 29, there being an aperture 49 located in the adjustable member 45, and registering with any desired one of the apertures 48 located in the extremity 44 of the horizontal bar 29, and held in engagement by means of the pin 50. 105 110

The cord 47 is extended over pulleys 51

attached to the wall 12, so as to permit the cord 47 to be attached to one extremity of the bell crank 52, as at 53, which is pivotably attached under the floor 13, as at 54, and 5 has its other extremity 55, in contact with the movable portion 56 of the floor 13, which is held normally in a flush position with the floor 13 by means of coil springs 57 conveniently located under the movable 10 portion 56 of the floor 13, the movable portion 56 having flanged edges 58 to engage grooves suitably located in the floor 13 to enable the coil springs 57 to hold the movable portion 56 in a flush position.

15 Referring in particular to the functioning or operating of my improved device:

It will be understood that the supplementary safe door may be raised above the safe door, as clearly described and heretofore set forth. It will be also understood that the supplementary safe door may be held in the above mentioned position by means of the pointed extremity of the catch lever when engaged with the notch of the catch 22, at which time the pointed lower extremity of the locking pin is engaged with one of the grooves in the upper edge of the catch lever.

20 It will be further understood that when the movable portion of the floor is stepped on, that the cord will be pulled which will disengage the catch lever, and the supplementary door will fall covering the safe door.

25 It will also be further understood that the catch lever and the catch may be engaged in a vertical position, or at slight angular relative positions by means of the plurality of grooves located in the horizontal bar, which will render the operation of 40 my improved device more sensitive, as may be required.

It will be further understood that the 45 plurality of apertures located in the extremity of the horizontal bar and the adjustable member will compensate for the heretobefore mentioned sensitiveness of operation of my improved device.

50 It will also be further understood that when the supplementary safe door is dropped, that the lock 59, attached to the supplementary safe door will lock the supplementary safe door in a closed position, and will also complete the circuits 60 and 61, 55 which will cause the batteries 62 and 63, or any convenient source of electric current, to ring the bells 64 and 65, gongs or signalling devices, respectively, which may be located at the police station, protective agency's office, or at any suitable convenient place.

60 While I have above described the preferred form, construction and arrangement of the several elements employed, it will be 65 understood that the device is, nevertheless,

susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:

1. In a device of the class described, having a supplementary slideable door and a depressible floor portion, the combination of a bell crank pivotally mounted on a stationary member intermediate of its ends, one end of said bell crank engaging against said depressible floor portion, a string connected to the other end of said bell crank, an adjusting member fastened to the other end of said string, said adjusting member having a longitudinal aperture and a transverse aperture, a rod slidably mounted on a stationary member, one end of said rod being formed with transverse apertures, and said end being engaged in the longitudinal aperture of said adjusting member, a pin engaged through said transverse apertures to hold said rod and adjusting member together, said rod being formed intermediate its ends with a series of notches, a spring pressed pin depending from a bracket secured to a stationary member, engaging one of said notches, said rod being formed at its other end with a yoke, a lever with an offset end pivotally mounted intermediate of its ends to a stationary member, the end of said lever remote from said offset being formed with an elongated aperture, a pin engaged in said yoke and passing through said elongated aperture, and a catch fixed to said supplementary slideable door, and engageable with the offset end of said lever.

2. In a device of the class described, associated with a wall having a supplementary slideable door and a depressible floor portion, the combination of a bell crank pivotally mounted on a stationary member intermediate of its ends, one end of said bell crank engaging against said depressible floor portion, a string connected to the other end of said bell crank, an adjusting member fastened to the other end of said string, said adjusting member having a longitudinal aperture and a transverse aperture, a rod slidably mounted on said wall, one end of said rod being formed with transverse apertures, and said end being engaged in the longitudinal aperture of said adjusting member, a pin engaged through said transverse apertures to hold said rod and adjusting member together, said rod being formed intermediate of its ends with a series of notches, a spring pressed pin depending from a bracket secured to said wall, engaging one of said notches, said rod being

- formed at its other end with a yoke, a lever with an offset end pivotally mounted intermediate of its ends to said wall, the end of said lever remote from said offset being formed with an elongated aperture, a pin engaged in said yoke and passing through said elongated aperture, and a catch fixed to said supplementary slidable door, and engageable with the offset end of said lever.
3. In a device of the class described, associated with a wall having a supplementary slidable door and a depressible floor portion, the combination of a bell crank pivotally mounted on a stationary member intermediate of its ends, one end of said bell crank engaging against said depressible floor portion, a string connected to the other end of said bell crank, an adjusting member fastened to the other end of said string, said adjusting member having a longitudinal aperture and a transverse aperture, a rod slidably mounted on said wall, by means of a bracket, one end of said rod being formed with transverse apertures, and said end being engaged in the longitudinal aperture 25 of said adjusting member, a pin engaged through said transverse apertures to hold said rod and adjusting member together, said rod being formed intermediate of its ends with a series of notches, a spring 30 pressed pin depending from a bracket secured to said wall, engaging one of said notches, said rod being formed at its other end with a yoke, a lever with an offset end pivotally mounted intermediate of its ends 35 to said wall, the end of said lever remote from said offset being formed with an elongated aperture, a pin engaged in said yoke and passing through said elongated aperture, and a catch fixed to said supplementary 40 slidable door, and engageable with the offset end of said lever.

In testimony whereof I have affixed my signature.

GEORGE KOWALSKI.
